UNITED STATES PATENT OFFICE.

CHARLES J. GADD, OF PHILADELPHIA, PENNSYLVANIA, ASSIGNOR TO THE
H. W. BUTTERWORTH & SONS COMPANY, OF PENNSYLVANIA.

APPARATUS FOR STEAMING FABRICS.

SPECIFICATION forming part of Letters Patent No. 578,008, dated March 2, 1897.

Application filed November 25, 1896. Serial No. 613,364. (No model.)

To all whom it may concern:

Be it known that I, CHARLES J. GADD, of the city and county of Philadelphia and State of Pennsylvania, have invented an Improvement in Machines for Steaming, Aging, or Drying Textile Fabrics, of which the following is a specification.

My invention has reference to machines for steaming, aging, &c., textile and other fabrics; and it consists of certain improvements which are fully set forth in the following specification and shown in the accompanying drawings, which form a part thereof.

My invention comprehends certain features of construction in machines of this class more especially designed for conveying the supporting-rods through the machine and manipulating them in such manner that they may support and guide the fabric or material being treated within the drying-room or closed chamber.

This invention is especially adapted for treating all flexible materials when in long strips either for drying, steaming, or other treatment. Thus the apparatus may be used for treating woven or textile fabrics, including dyed or printed goods, oil-cloths, and also wall-paper.

In carrying out my invention I arrange a pair of endless or other suitable conveyers within a chamber and provide them with hooks or devices for supporting and carrying the rods, and in combination therewith I provide receiving-guides, upon which the rods are automatically deposited by the conveyers, and automatic reciprocating pushers moved forward under the action of power devices to force the rods over the guides and into a pair of grooved or other suitable guides arranged longitudinally of the chamber or room, near its upper part. My preferred form of power devices comprehends suitable rack and gears adapted to impart a rapid forward motion to the pushers and a slow return movement, the object of which is to quickly place the rod acted upon into proper operative position with respect to the longitudinal or grooved guides and cloth, and so time the pusher that it is brought into proper initial position for a second action just in time, or

thereabout, to act upon another rod placed in position upon the guide by the conveyers.

My invention also comprehends numerous details of construction in a machine of this character, all of which will be fully described hereinafter, and more particularly shown in the accompanying drawings, in which—

Figure 1 is a sectional elevation of a machine for steaming, aging, or drying textile or other fabrics embodying my invention. Fig. 2 is a transverse sectional elevation of same on line $x-x$. Fig. 3 is an enlarged view of a portion of Fig. 1, showing the power mechanism. Fig. 4 is a similar view of a modified type of power mechanism. Fig. 5 is a sectional plan view of another modification of power mechanism embodying my improvements. Fig. 6 is a sectional elevation of same. Fig. 7 is a sectional elevation, and Fig. 8 is a front elevation, of the controlling devices for the rods and fabric at the discharge end of the longitudinal guides on an enlarged scale.

A is a closed chamber of any suitable construction and may be provided with a perforated or slatted floor A' and steaming and heating pipes A^2 close to the bottom. Arranged within the chamber and traveling over guide sprocket-wheels b b' near each side is an endless conveyer-chain B . The tension of the chains is secured by weights D , applied to the lower guide-wheels b . By employing guide-wheels b' near the upper part of the chamber and at a lower elevation than the upper wheels b the chains or conveyers are caused to move vertically for a short distance and then horizontally and below the grooved or longitudinal guides E , which are arranged longitudinally between the said vertical parts of the conveyer-chains. Suitable guides B' are arranged to sustain the weight of the horizontal parts of the conveyers to prevent sagging and swinging. The conveyer-chains are provided at intervals in their length with hooks C , loosely pivoted, so as to automatically adjust themselves.

F are a series of rods having collars or heads f at each end of somewhat larger diameter and adapted to run in or upon the guides E , as clearly shown. At the forward end of the

guides E there is arranged a horizontal guide-way *e*, which projects somewhat inward on one side of the grooved guides E, as shown in Fig. 5. This guide *e* receives the rod F and 5 leaves the collars or heads thereof extended over and in line with the grooves of the guide E. Small pawls *m* extend downward from an extension on the grooved guide E, so as to form a slight obstruction to the accidental 10 rolling of a rod from the extreme end of the guide *e*, the position of the said rod when deposited by the hooks C being clearly shown in dotted lines in Figs. 3 to 6. Normally the 15 grooved guides E are filled with a series of parallel rods F, and in the operation of the machine a rod is forced into one end of the said guides E simultaneously with the removal or discharge of a rod at the opposite end, so that there are always the same number of rods 20 acting upon the fabric W, which is fed through the chamber and sustained in loops upon the said rods, as clearly shown in Fig. 1. The fabric enters the chamber A between feeding-rollers II, and after being treated emerges 25 by being drawn out of the chamber between the plates I' I'.

When the rod is brought to a position upon the guide *e* by the endless conveyers, it is left there, while the hooks continue to travel, and 30 while this operation is taking place the fabric W is descending to form a new loop. When the loop is formed, the pushers *k* are moved forward so that they strike the heads or collars of the rod and move it under the pawl 35 and forward against the rods within the guides E. The heads or collars of the various rods properly space them and prevent the cloth from rubbing upon itself. When the pushers move forward, they act upon both ends 40 of the rod alike and exert a sufficient force to move the entire series of rods through or over the guides. The rod so moved by the pushers is forced under the pivoted friction-fingers *g*, which thereby hold the cloth from 45 slipping over the said rod and also insure its further feeding to form a new loop. These friction-fingers are very clearly shown in Fig. 3, in which we have the fingers proper, *g*, adjustably secured to the free end of a bell- 50 crank arm or lever G, provided with an adjusting-screw *i*, to adjust it so as to limit the downward movement of the fingers *g*. A weight *G'* is adjustably clamped to the arm G, so as to exert any desired tension upon the 55 fabric. There are a number of these fingers employed, as shown in Fig. 2, and they are all connected to a cross-beam U, which also carries the guides E.

The pushers *k* are secured to reciprocating frames K, provided with internal racks K' K², facing each other, and are adjustable at *k* to compensate for wear. A transverse shaft L has secured to it segmental gears M and N, the former adapted to engage with 60 the rack K' and the latter with the rack K². It will be seen that when this shaft rotates in the direction of the arrow, Fig. 3, the action

of the gear M with the rack K' causes the pusher *k* to be moved with considerable rapidity forward to transfer the rod from the dotted position to the solid position under the fingers G, and a further movement brings the gear N into operation with the rack K² and returns the pusher at a slower speed. When fully returned, it remains at rest for a 70 period until the gear M again comes into contact with the rack K', when the operation is repeated. At the period of rest, however, a new rod is deposited upon the guides *e* by the conveyer. The frame K of the pusher is 75 guided in a horizontal guide P, so that it reciprocates with great steadiness. The guide sprocket-wheels b' are loosely supported upon the shafts L as they rotate under the action of the conveyers B in the opposite direction 80 to the gears. As shown in Fig. 2, there are two of the shafts L, since it would be impracticable to run the shaft all the way across on account of the descending fabric. These shafts, however, are connected by suitable 85 gearing L' and positively driven by a shaft L². (See Fig. 2.) Gears L² transmit power from the shafts L to the driving sprocket-wheels b at the top of the chamber.

Whenever a new rod is pushed into position at the forward end of the guides E, a rod is liberated at the rear or discharge end and moves upon the inclined guides E' until it comes to rest in a position to be automatically taken up by the hooks C, Fig. 1. Levers H, 90 counterweighted at *h*, may be employed to offer a resistance to the accidental displacement of the rods near the discharge end, so as to arrest any tendency to roll under the impact given at the forward end. The levers H are so shaped at the bottom as to rest gently upon the fabric on the rod to stop its slipping down and are provided with a lateral cam projection H', Figs. 7 and 8, which acts upon the rod next to the rear and between the head and the fabric, so that when the rods are all moved forward this last-mentioned rod, acting upon the part H', raises the lever H so that it shall not drag over the cloth or material being treated, but upon the 95 passage of the rod under the cam part H' it drops and once more allows the lever H to rest upon the fabric and last-mentioned rod. In this way only one rod at a time is liberated and injury to the fabric prevented. As 100 the rods are pushed toward the rear they are moved one at a time from under the pivoted lever mechanism H and then by gravity roll upon the inclined guides E' into position to be taken away by the hooks of the conveyer 105 and ultimately returned below the fabric and brought up to the forward or feeding end previously described.

In place of using a pair of endless conveyers, as shown, it is evident that the conveyers 110 may be formed in any suitable manner, so long as they have a capacity for conveying the rods through the chamber or from the discharge end to the feeding end of the horizon-

tal or grooved guides. It is also evident that with regard to the guides E the upper flange may be omitted, so that, strictly speaking, they would not be grooved guides. In fact, 5 any form of guides suitable to the purpose may be used.

It will be observed from an examination of Fig. 3 that the upper surface of the guide e is on a level with the bottom of the rods f, so 10 that when moved forward their heads or collars are properly brought into position in the guides E.

In place of the particular means for pushing the rods into position above described I 15 may employ a modification thereof, as indicated in Fig. 4, in which a crank-wheel O is provided with a crank-pin o, working in a transverse or vertical slot on a reciprocating bar or frame O', to which the pusher k is secured. It will be seen that upon rotating the 20 crank O the pusher will be moved forward and backward at intervals, though in this case the movements will be uniform. By 25 properly shaping the transverse groove for the crank-pin, however, the reciprocations may be made irregular, corresponding to that of Fig. 3.

In the modification shown in Figs. 5 and 6 the pusher k is secured to a frame S, having 30 a rack P², guided in a horizontal guide P³ and moved backward under the action of a weight T, attached to a chain s, guided by a pulley S' and connecting with the pusher-frame S. The forward movement of the 35 pusher is produced by a segmental gear E', meshing with the rack P², and in all material respects corresponds to the gear and rack K' of Fig. 3. In this manner the forward motion is positively performed with considerable 40 rapidity by a rack and gear, while the return motion is performed by the action of gravity. At the end of the return motion the parts may remain at rest for a period of time during 45 which a new rod is put into position upon the guide e.

While I prefer to make the gears M and N of different diameters and so set as to produce no appreciable period of rest at one end of the reciprocation of the frame K and a considerable period of rest at the other end, the motions may be made without the period of rest and also without the difference in speed, if so desired, by simply properly proportioning the gears.

55 In some cases, as in drying wall-paper or oil-cloths, the apparatus would be set up in a large room, which need not be tightly enclosed, as in the case of the chamber A. Hence I do not confine myself to the use of any in- 60 closing chamber.

While I prefer the construction shown, I do not limit myself to the details thereof, as they may be modified in various ways without departing from the principle of my invention.

What I claim as new, and desire to secure by Letters Patent, is—

1. In a machine for steaming, aging, or drying textile or other fabric, the combination of two longitudinal guides arranged at a distance apart and having their forward ends provided with horizontal guides unobstructed from above, transverse rods over which the fabric is looped supported by the said guides, suitable conveying devices adapted to deposit rods at intervals upon the horizontal guides, reciprocating pushers for simultaneously pushing both ends of the rod over the horizontal guides, pusher-frames guided in suitable guides, rotary shafts, and power-transmitting connections between the said shafts and the reciprocating pusher-frames for operating the pushers. 70

2. In a machine for steaming, aging, or drying textile or other fabric, the combination of two longitudinal guides arranged at a distance apart and having their forward ends provided with horizontal guides unobstructed from above, transverse rods over which the fabric is looped supported by the said guides, 75 suitable conveying devices adapted to deposit rods at intervals upon the horizontal guides, reciprocating pushers for simultaneously pushing both ends of the rod over the horizontal guides, pusher-frames guided in suitable guides, rotary shafts, and power-transmitting connections between the said shafts and the reciprocating pusher-frames for operating the pushers. 80

85

3. In a machine for steaming, aging, or drying textile or other fabric, the combination of two longitudinal guides arranged at a distance apart and having their forward ends provided with horizontal guides unobstructed 90

from above, transverse rods over which the fabric is looped supported by the said guides, suitable conveying devices adapted to deposit rods at intervals upon the horizontal guides, 95

reciprocating pushers for simultaneously pushing both ends of the rod over the horizontal guides, pusher-frames guided in suitable guides, rotary shafts, and power-transmitting connections between the said shafts and the reciprocating pusher-frames for operating the pushers with a quick forward motion and a slow return motion. 100

105

3. In a machine for steaming, aging, or drying textile or other fabric, the combination of two longitudinal guides arranged at a distance apart and having their forward ends provided with horizontal guides unobstructed 110

from above, transverse rods over which the fabric is looped supported by the said guides, suitable conveying devices adapted to deposit rods at intervals upon the horizontal guides, 115

reciprocating pushers for simultaneously pushing both ends of the rod over the horizontal guides, pusher-frames provided with two racks and guided in suitable guides, rotary

120 shafts, and segmental gears of different diameters respectively meshing with the two racks of each pusher-frame for moving the

125 said frames forward with a greater speed than that imparted on the backward movement.

4. In a machine for steaming, aging, or drying textile or other fabric, the combination of two longitudinal guides arranged at a distance apart and having their forward ends provided with horizontal guides unobstructed 130

from above, transverse rods over which the fabric is looped supported by the said guides, suitable conveying devices adapted to deposit rods at intervals upon the horizontal guides, 135

reciprocating pushers for simultaneously pushing both ends of the rod over the horizontal guides, pusher-frames provided with two racks guided in suitable guides, rotary

140 shafts, and segmental gears of different diameters respectively meshing with the two racks of each pusher-frame for moving the

145 said frames forward with a greater speed than that imparted on the backward movement.

said frames forward with a greater speed than that imparted on the backward movement and so formed in the arc of the circle which they include as to produce a period of rest of 5 the pusher-frame upon its extreme backward movement.

5. In a machine for steaming, aging, or drying textile or other fabric, the combination of two longitudinal guides arranged at a distance apart and having their forward ends provided with horizontal guides unobstructed from above, transverse rods over which the fabric is looped supported by the said guides, suitable conveying devices adapted to deposit rods at intervals upon the horizontal guides, reciprocating pushers for simultaneously pushing both ends of the rod over the horizontal guides, pusher-frames guided in suitable guides, rotary shafts, power-transmitting connections between the said shafts and the reciprocating pusher-frames for operating the pushers, a series of pivoted friction-creating fingers for holding the fabric upon the rods when pushed forward by the 25 pushers, and weights for adjusting the tension of said friction-creating fingers upon the fabric.

6. In a machine for steaming, aging, or drying textile or other fabric, the combination of 30 two longitudinal guides arranged at a distance apart and having their forward ends provided with horizontal guides unobstructed from above, transverse rods over which the fabric is looped supported by the said guides, suitable conveying devices adapted to deposit rods at intervals upon the horizontal guides, reciprocating pushers for simultaneously pushing both ends of the rod over the horizontal guides, pusher-frames guided in 35 suitable guides, rotary shafts, power-transmitting connections between the said shafts and the reciprocating pusher-frame for operating the pushers, a series of pivoted friction-creating fingers for holding the fabric upon the rods when pushed forward by the pushers, weights for adjusting the tension of said friction-creating fingers upon the fabric, and means for limiting the downward movement 45 of the friction-creating fingers.

50 7. In a machine for steaming, aging, or drying textile or other fabric, the combination of two longitudinal guides arranged at a distance apart and having their forward ends provided with horizontal guides unobstructed from above, transverse rods over which the fabric is looped supported by the said guides, suitable conveying devices adapted to deposit rods at intervals upon the horizontal guides, reciprocating pushers for simultaneously pushing both ends of the rod over the horizontal guides, pusher-frames guided in suitable guides, rotary shafts, power-transmitting connections between the said shafts and the reciprocating pusher-frames for operating 55 the pushers, a series of pivoted friction-creating fingers for holding the fabric upon 60

the rods when pushed forward by the pushers, weights for adjusting the tension of said friction-creating fingers upon the fabric, and adjusting devices for adjusting the extent of 70 downward movement of the friction-creating devices without limiting the upward movement thereof.

8. In a machine for steaming, aging, or drying textile or other fabric, the combination of 75 two longitudinal guides arranged at a distance apart and having their forward ends provided with horizontal guides unobstructed from above, transverse rods over which the fabric is looped attached to the said guides, 80 suitable conveying devices adapted to deposit rods at intervals upon the horizontal guides, reciprocating pushers for simultaneously pushing both ends of the rod over the horizontal guides, pusher-frames guided in suitable guides, rotary shafts, power-transmitting connections between the said shafts and the reciprocating pusher-frames for operating the pushers, inclined discharging-guides at the rear of the longitudinal guides and from 85 which the conveyers are adapted to remove the liberated rods, and friction-creating devices acting upon the transverse rods near the discharging end of the guides to offer a resistance to their premature liberation from 90 the longitudinal guides.

9. In a machine for steaming, aging, or drying textile or other fabric, the combination of two longitudinal guides arranged at a distance apart and having their forward ends 100 provided with horizontal guides unobstructed from above, transverse rods over which the fabric is looped supported by the said guides, suitable conveying devices adapted to deposit rods at intervals upon the horizontal guides, reciprocating pushers for simultaneously pushing both ends of the rod over the horizontal guides, pusher-frames guided in suitable guides, rotary shafts, power-transmitting connections between the said shafts and the 105 reciprocating pusher-frames for operating the pushers, inclined discharging-guides at the rear of the longitudinal guides and from which the conveyers are adapted to remove the liberated rods, friction-creating devices 110 acting upon the transverse rods near the discharging end of the longitudinal guides to offer a resistance to their premature liberation from the horizontal guides, and means to adjust the tension of said friction-creating 115 devices.

10. In a machine for steaming, aging, or drying textile or other fabric, the combination of the longitudinal guides E having the horizontal guide extensions e, the reciprocating frames K having pushers k and provided with racks K' and K², segmental gears M and N respectively adapted to said racks K' and K², and power devices for rotating the said segmental gears.

11. In a machine for steaming, aging, or drying textile or other fabric, the combination

- of the longitudinal guides E having the horizontal guide extensions e, the reciprocating frame K having pushers k and provided with racks K' and K², segmental gears M and N respectively adapted to said racks K' and K², power devices for rotating the said segmental gears, and pawls m extending downward and in the path of the transverse rods being operated upon by the pushers k.
12. In a machine for steaming, aging, or drying textile or other fabric, the combination of the longitudinal guides E having the horizontal extensions e, reciprocating pushers k carried by frames each having a rack, a rotating segmental gear adapted to mesh with each of said racks to produce a forward motion of the pushers and their frames, and means to return the pushers and their frames when liberated by the gears.
13. In a machine for steaming, aging, or drying textile or other fabric, the combination of longitudinal guides for the transverse supporting-rods, reciprocating pushers for moving the rods over the guides, and rotating power devices for intermittently acting upon the pushers for causing their reciprocation.
14. In a machine for steaming, aging, or drying textile or other fabric, the longitudinal guides in combination with transverse rods for supporting the fabric, means for feeding the rods over the guides, and friction-creating devices for holding the rod and fabric consisting of fingers g carried in pivoted arms G and provided with adjusting devices i for adjusting the downward movement of the arm G.
15. In a machine for steaming, aging, or drying textile or other fabric, the longitudinal guides in combination with transverse rods for supporting the fabric, means for feeding the rods over the guides, friction-creating devices consisting of fingers g carried in pivoted arms G and provided with adjusting devices i for adjusting the downward movement of the arm G, and adjustable weights G' for creating the necessary downward pressure of the fingers upon the fabric and rods to hold them in position when pushed forward.
16. In a machine for steaming, aging, or drying textile or other fabric, the combination of horizontal guides, transverse rods attached to said guides for supporting the fabric, means to move the rods over the guides, and friction-creating devices for holding the fabric upon the rods consisting of pivoted arms G having a weight G' and the friction-creating finger g vertically adjustable in the arm G and means

for adjusting the downward movement of the arm G.

17. In a machine for steaming, aging, or drying textile or other fabric, the combination of longitudinal guides, a series of transverse rods for supporting the fabric in loops sustained by said guides, power devices for moving said rods intermittently over the said guides, movable friction-creating devices acting upon the rearmost rod in the guides to hold the cloth upon the rod and hold the rod against accidental liberation, and cam devices controlled by the next adjacent rod to raise the friction-creating devices to liberate the fabric and rearmost rod so that it may be discharged.

18. In a machine for steaming, aging, or drying textile or other fabric, the combination of longitudinal guides, a series of transverse rods for supporting the fabric in loops sustained by said guides, power devices for moving said rods intermittently over the said guides, friction-creating devices consisting of a pivoted lever having a pressure-foot acting upon the rearmost rod in the guides to hold the cloth upon the rod and hold the rod against accidental liberation, and cam devices carried by the pivoted lever and displaced laterally so as to be acted upon and be controlled by the part of the next adjacent rod not covered by the fabric to raise the friction-creating devices to liberate the fabric and rearmost rod so that it may be discharged.

19. In a machine for steaming, aging, or drying textile or other fabric, the combination of longitudinal guides, a series of transverse rods for supporting the fabric in loops sustained by said guides, power devices for moving said rods intermittently over the said guides, movable friction-creating devices acting upon the rearmost rod in the guides to hold the cloth upon the rod and hold the rod against accidental liberation, cam devices controlled by the next adjacent rod to raise the friction-creating devices to liberate the fabric and rearmost rod so that it may be discharged, oblique discharge-guides at the discharge end of the longitudinal guides to receive the liberated rods, and conveyer devices for removing the liberated rods and returning them to the opposite end of the longitudinal guides.

In testimony of which invention I have hereunto set my hand.

CHARLES J. GADD.
